WHEELED TOY

Peter Mariani, Thomaston, Conn.

Application March 17, 1945, Serial No. 583,189

10 Claims. (Cl. 46—103)

1 This invention relates to toys, and more particularly to a wheeled toy figure representing a seal having a balanced ball on the end of a reciprocating and rotating vertical stick carried in the mouth of said seal.

One object of the present invention is to provide a wheeled toy of the above nature in which the seal figure comprises an upstanding block having flat sides, mounted to roll upon the floor, the mounting including a pair of wheels and an axle which carries a cam engaging a collar on the lower end of the stick, upon the upper end of which the ball is carried.

Another object is to provide a wheeled toy of the above nature, in which the collar on the lower end of the stick is pressed downwardly by a spring to assist the action of gravity in returning the ball to its lowermost position as the stick is reciprocated.

A further object is to provide a wheeled toy of the above nature which is supported at the rear by a swiveled "flipper" which will permit the figure to follow the body with the minimum of friction as the latter is pulled across the floor.

A further object is to provide a wheeled toy of the above nature which will be simple in construction, automatic in operation, inexpensive to manufacture, easy to install and manipulate, compact, ornamental in appearance, and very efficient and durable in use.

With these and other objects in view, there have been illustrated on the accompanying drawings four forms in which the invention may conveniently be embodied in practice.

In the drawings,

Fig. 1 represents a front view, partly in section, of the wheeled toy embodying the invention.

Fig. 2 is a side view of the same, also shown partly in section.

Fig. 3 is a transverse sectional view, taken along the line 3—3 of Fig. 2 on a larger scale, looking downwardly in the direction of the arrows.

Fig. 4 is an enlarged longitudinal sectional view of the same, taken along the line 4—4 of Fig. 1.

Fig. 5 is an enlarged fragmentary view of a modified form of cam and collar mechanism for reciprocating the ball-carrying stick.

Fig. 6 is a fragmentary view, partly in section, of a modified form of rear flipper and ball wheel mounted therein.

Fig. 7 is a fragmentary view, partly in section, of another modified form of rear flipper having a vertical stud mounted to swivel in the lower end of the figure body.

Referring now to the drawings in which like

reference numerals denote corresponding parts throughout the several views, the numerals 10 and 11 indicate a pair of forward cylindrical wheels mounted to rotate upon an axle 12 and being spaced apart by a pair of cylindrical bushings 13, 14 which serve to hold the body 18 of the toy in centralized position.

The axle 12 has an elliptical plate cam 15 rigidly secured thereon eccentrically, said cam having an annular beveled section 16 and a flat rim 17. The cam 15 is located within a recess 17a formed in the lower end of the body 18 which comprises a vertical block with flat sides, as shown. The upper portion of the body 18 has a section 19 representing the neck and head of a seal, and a narrow rear depending flipper 20, as most clearly shown in Fig. 2.

At the forward end of the body block 18 is a depending section 21, representing the forward flipper, which is split to permit the oval plate cam 15 to rotate therewithin. The body block 18 is also provided with a depending central rectangular bearing section 22 which is also split to embrace the cam 15.

In order to produce the effect that a ball is being balanced on the head of the seal figure, provision is made within the interior of the block 18 of a vertical bore 23, rectangular in cross section, within which is a vertical stick 24, preferably round in cross section. The stick 24 has a ball 25 rigidly mounted upon its upper end and on its lower end has a rigid cylindrical collar 26 adapted to engage the beveled section 16 of the oval plate cam 15.

The bore 23 is open at one side to facilitate the insertion of the stick 24 and a pair of square hollow bearing blocks 27, 28 loosely surrounding said stick, and which are adapted to be located permanently adjacent the top and bottom of said bore, respectively. The blocks 27, 28 are held frictionally within said bore 23 by means of a side vertical cover strip 29 secured to said blocks, and which is so arranged that the stick 24 will be maintained substantially in vertical alignment with the axle 12 below it.

In order to assist the action of gravity in returning the ball and stick to the lowermost position shown in Fig. 1, provision is made of a coiled spring 30 located between the bottom block 28 and the collar 26, as shown in Fig. 1.

The rear flipper 20 of the block 18 is provided with a spherical recess within which a small ball 31 is mounted for rotation freely in all directions, said ball being held in position by a retaining strip 32 placed in front of said ball, as shown in Fig. 2.

The wheeled toy is adapted to be pulled around upon the floor, or any other flat surface, by means of a cord 33 attached to an eye 34 secured to the top portion of the front flipper 21.

Operation

When the wheeled figure toy is pulled across the floor by means of the cord 33, the eccentric oval cam 15 on the axle 12 will reciprocate the ball 25 on the stick 24 twice for each rotation of the wheels 10, 11. At the same time the frictional engagement of the beveled section 16 of the cam 15 with the lower edge of the collar 26 will cause the stick to rotate at varying speeds around its own axis and produce the illusion of a seal balancing a rolling ball upon the end of the stick carried in its mouth.

In the second form of the invention shown in Fig. 5, instead of employing a beveled cam, as in Figs. 1-4, a cam 35 is used having a horizontal outer rim, which is adapted to engage a collar 36 located on the lower end of the stick 24, which collar has a beveled lower section 37 for cooperatively engaging with the edge of the cam 35 to produce the twisting action of the reciprocating stick, as with the first form of the invention.

In the third form of the invention shown in Fig. 6, instead of employing a rear supporting ball 31, which is mounted to rotate in all directions, provision is made of a ball wheel 39 mounted to rotate only around the axis of a horizontal axle pin 40 mounted within the rear flipper 38.

In the fourth form of the invention, shown in Fig. 7, provision is made of a block 41 which is provided on its rear end with a swinging rear flipper 42 loosely connected therewith. The flipper 42 has a supporting ball 43 capable of rotating around any axis, and the rear end of the block 41 has a cylindrical vertical recess 44 for receiving a swivel stud 45 upstanding from said rear flipper 42. The stud 45 has a reduced upper neck 46 forming a groove within which passes a horizontal cross pin 47 for holding the rear flipper in operating position. The operation of this fourth form of the invention is similar to that of the first form, but in this case the rear flipper is capable of swinging in the direction of movement of the wheeled toy as it is pulled across the floor.

While there have been disclosed in this specification four forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a wheeled toy, a vertical body block having a rear supporting section, said block having a pair of forward supporting wheels rigidly connected by a horizontal axle, a plate cam mounted on said axle and located in the center portion of said block, said block having a vertical bore, a stick having a ball rigidly secured to its upper end located in said bore, the lower end of said stick having means for continuously cooperatively engaging with the rim of said cam to cause said stick to reciprocate vertically and also to twist around its axis when said toy is moved across the floor.

2. The invention as defined in claim 1, in which said cam is provided with a beveled side section, and said stick has a cylindrical collar on its lower end.

5. 3. The invention as defined in claim 1, in which said cam is provided with a horizontal rim, and said stick has a beveled collar for cooperatively engaging said rim.

4. The invention as defined in claim 1, in which the rear leg of said figure toy has a swiveled support mounted to swing about a vertical axis as said toy is moved across the floor.

5. The invention as defined in claim 1, in which said body block is provided with a vertical strip which carries a pair of bearing blocks for embracing the reciprocating stick, said stick, strip, and blocks being insertable laterally into said vertical bore.

6. The invention as set forth in claim 1, in which spring means are provided for pressing said collar downwardly to aid the force of gravity in returning said ball-carrying stick to its lowermost position during the reciprocation thereof.

7. In a wheeled toy, a vertical body block having a rear supporting section, said block having a pair of forward supporting wheels rigidly connected by a horizontal axle, a plate cam mounted on said axle and located in the center portion of said block, said block having a vertical bore, a stick having a ball rigidly secured to its upper end located in said bore, the lower end of said stick having means for continuously cooperatively engaging with the rim of said cam to cause said stick to reciprocate vertically and also to twist around its axis at varying speeds when said toy is moved across the floor.

8. In a wheeled toy, a vertical body block having a rear supporting section, said block having a pair of forward supporting wheels rigidly connected by a horizontal axle, an eccentric plate cam mounted on said axle and located in the center portion of said block, said block having a vertical bore, a stick having a ball rigidly secured to its upper end located in said bore, the lower end of said stick having means for continuously cooperatively engaging with the rim of said cam to cause said stick to reciprocate vertically and also to twist around its axis at varying speeds when said toy is moved across the floor.

9. In a wheeled toy, a vertical body block shaped to represent a seal having a rear supporting section, said block having a pair of forward supporting wheels rigidly connected by a horizontal axle, a plate cam mounted on said axle and located in the center portion of said block, said block having a vertical bore, a stick having a ball rigidly secured to its upper end located in said bore, the lower end of said stick having means for continuously cooperatively engaging with the rim of said cam to cause said stick to reciprocate vertically and also to twist around its axis when said toy is moved across the floor.

10. In a wheeled figure toy, a vertical body block having a rear supporting section, said section being provided with a ball roller mounted to rotate on a horizontal pin secured in said section, said rear section being separately movable on said block and connected to said block by a vertical swivel stud having a groove at its upper end, and a horizontal pin in said block and passing through said groove to secure said rear section to said block.

PETER MARIANI.
